Term of patent 14 years

Int. Cl. D14—02

U.S. Cl. D26—5 C

FIG. 4

FIG. 5

FIG. 1 is a perspective view of an acoustic coupled remote data entry terminal showing our new design.

FIG. 2 is a front elevational view thereof.

FIG. 3 is a rear elevational view thereof.

FIG. 4 is a top plan elevational view thereof.

FIG. 5 is a side view thereof.

The broken line disclosure of the numerals in FIGS. 1 and 4 is for illustrative purposes only and forms no part of the claimed design. The cord has been shown fragmentarily in FIGS. 3, 4 and 5. For ease of illustration the side of the device which is not shown in FIG. 5 is substantially identical to that which is shown.

We claim:

The ornamental design for an acoustic coupled remote data entry terminal or similar article, as shown and described.
